Libratone Zip Classic Product, exact date unknown, dated at least as early as May 2014. U.S. Appl. No. 29/549,591.*

Primary Examiner — Paula Allen Greene

(74) *Attorney, Agent, or Firm* — Dykema Gossett PLLC

(57) **CLAIM**

The ornamental design for a loudspeaker, as shown and described.

DESCRIPTION

FIG. 1 is a rear, side, and top perspective view of a first embodiment of a loudspeaker showing my design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a front, side, and top perspective view of a second embodiment of a loudspeaker showing my design;

FIG. 7 is a front elevational view of FIG. 6;

FIG. 8 is a rear elevational view of FIG. 6;

FIG. 9 is a top plan view of FIG. 6; and,

FIG. 10 is a bottom plan view of FIG. 6.
